UNITED STATES PATENT OFFICE.

EBENEZER FISHER, OF EGG HARBOR CITY, NEW JERSEY.

VISE.

999,978.

Specification of Letters Patent. Patented Aug. 8, 1911.

Application filed September 24, 1909. Serial No. 519,395.

To all whom it may concern:

Be it known that I, EBENEZER FISHER, a subject of the King of Great Britain, residing at Egg Harbor City, in the county 5 of Atlantic and State of New Jersey, have invented certain new and useful Improvements in Vises, of which the following is a specification.

This invention relates to improvements 10 in vises and other clamping devices in which a sliding jaw is employed. Heretofore, in devices of this character the movable jaw is generally actuated and held by pressure applied thereto in a direction 15 which, while advancing the same, fails to apply at all times a seating pressure of the movable jaw upon its base, with the result that such movement of the jaw takes place under the clamping strain as to throw the 20 clamping face of the movable jaw out of parallelism with the clamping face of its opposing jaw, thereby causing the clamping action to be present upon a part only of the clamping surface of the jaws and the 25 work held therebetween with the consequent effect of insecure clamping of the work or the mutilation thereof from the necessity of undue clamping strain.

Therefore, the principal object of the 30 present invention is to provide a simple construction of clamping device in which the movable jaw member may be quickly positioned upon its base and be actuated for clamping by the application of a pressure 35 applied at a downward inclination thereon so that while advancing the movable jaw member it will force the same at all times to its base and thereby maintain the parallelism of the clamping faces of the jaws and 40 also render ineffective looseness or wear of the parts, which is the chief defect of wrenches generally.

The invention consists in so combining 45 the movable jaw member of a clamping device with its base and its actuating means that the pressure of the actuating means upon the movable jaw member will be on a downward inclination at all times; and the invention further consists in providing ad- 50 justable locking means by which the actuating means is secured to the base of the clamping device and which under the strain of the actuating device in applying pressure to the movable jaw on a downward in- 55 clination will the more firmly bind the actuating device to the base and without caus-

ing the actuating device to have any movement away from the base, thus providing against any movement of the actuating means that will be in opposition to its application of pressure upon the movable jaw at a downward inclination. 60

The invention also consists of certain other novel features in the arrangement and construction of parts, all as hereinafter described and specifically set forth in the appended claims. 65

In the accompanying drawings illustrating my invention, Figure 1, is a view in side elevation of a vise constructed in accordance 70 with the invention, Fig. 2, is a vertical longitudinal section taken centrally of Fig. 1, Fig. 3, is a top view, Fig. 4, is an end view, Fig. 5, is a detail, showing in perspective the ratchet block with the actuating screw, 75 Fig. 6, is a perspective view showing a portion of the bed of the vise with its movable jaw thereon, Fig. 7, is a detail showing the teeth of the ratchet bar and ratchet block in their closest engagement, Fig. 8, is a detail showing the position of the ratchet teeth 80 in their initial engagement.

Referring to the drawings, 1 designates the base or bed portion of the device having a fixed jaw 2 at one end. The bed portion 85 is preferably formed of two integral parts 1^a and 1^b having a slot 3 formed between them, into which slot is secured a rack-bar 4 so as to be spaced apart from the two parts of the bed portion, and this rack-bar 90 is held by means of the tapering bolts 5 and 5, which also serve to bind the two portions of the bed together.

6 designates the movable jaw slidably mounted upon the bed, and is preferably 95 formed with the two foot extensions 6^a and 6^b extending on each side of the slot 3 for the purpose of securing a firmer seating of the jaw on the bed while under strain.

The means for actuating the movable jaw 100 member consists of the screw 7 operating in the threaded bore 8 in the locking ratchet block 9. This actuating screw is arranged to lie at all times in the slanted position shown, so that its forward end face 7^a when 105 brought into contact with the movable jaw, will be against the bearing face 6^c of said jaw which face is at right angles to the axis of the screw 7. By this arrangement of actuating screw and bearing faces the pressure applied to the jaw 6 is in a forward 110 and downward direction which while ad-

vancing the jaw holds it to its bed. This principle of action presupposes that during the application of pressure the screw 7 will not be movable away from the bed as any such movement, tilting or otherwise, at the point of pressure during the application of pressure will defeat this principle of operation. It has therefore been provided that the pressure in clamping will in its backward 10 push upon the rack bolt 9 force the same at all times firmly downward upon the rack-bar, and firmly clamp the rack-block and rack-bar together. This is accomplished by forming the resisting walls 15 of the teeth of the engaging racks on an incline so that by their overhang one upon the other they will interlock and at the same time draw together under the clamping strain, as more fully illustrated in Figs. 7 20 and 8, which show in detail the loose position of the engaging racks, and the position when under pressure.

The ratchet block 9 is preferably channeled from its underside to receive and hold 25 the rack bar 10, the same being secured therein by bolts 11, and this rack-bar is seated sufficiently within the channel to permit the ratchet block to straddle the rack bar 4, thus maintaining the said block with its 30 actuating screw in operating position thereon at all times and permitting the ready placing of the block at any part upon the rack 4.

The base or body of the device is provided 35 at its fixed jaw with a downward cylindrical extension 12 which forms a pivot therefor and which is seated within a hollow cylindrical support 13 having a base 14 for the firm attachment thereof to a work 40 bench or other suitable fixed support. For the purpose of effectively and quickly binding the bed of the device at any position at any angle to which it may be turned, the hollow support member 13 is provided 45 with a boss 15 in which and extending through the wall of the supporting member is a bore 16 formed on a downward inclination and partly threaded to receive a binding screw 17. The pivot member 12 is provided 50 with an annular groove 18 to register with the opening of the bore 16 and presents a beveled face that is at right angles with the axis of said bore and receives in bearing contact therewith either the set 55 screw 17 or preferably as shown a small cylindrical bearing block of hard fiber or other suitable material which will lie partly in the said annular groove and partly in said bore and be operated upon by the screw to bind 60 the parts in fixed relation. It will be understood that by reason of the application of a binding pressure downward as well as inward the pivotal member 12 is not only acted upon but that portion of the base or 65 bed of the device resting on the top of the

cylindrical support 13 will be also forced down into binding contact therewith.

The cylindrical support 13 is provided with an annular bevel 19 at its base for the purpose of providing a bearing for a strut 70 20 which extends downward from the overhanging portion of the bed of the device where it is detachably held against a shoulder or heel 21 by the set screws 22. At the lower end the strut 20 is formed to fit the 75 curve of the annular bevel 19 and while giving support to the outer end of the bed of the device also causes binding to take place as the result of any strain applied downward upon said bed to bring about an automatic binding of the device upon its support, which will prevent accidental rotation. 80

I am aware that it is not new to arrange the actuating screw of a clamping device upon an incline nor to cause the adjustable 85 means for supporting the actuating screw to lock upon the base of the clamping device under the pressure of the said screw. The present invention while involving said features provides a construction that prevents 90 any raising or tilting of the actuating screw support and for this purpose makes provision for a slight lowering movement thereof, so that the direction of the line of force of the pressure upon the movable jaw will be 95 always forward and downward thereon, as any interruption of this action, as by a temporary lifting of the actuating screw would be unproductive of the ends attained by the 100 invention.

Having thus fully described my invention, what I claim and desire to secure by Letters Patent, is:

1. In a clamping device, the combination with a bed member carrying a jaw and a 105 ratchet face, of a coöperating jaw slidably mounted on said bed member and free of operative engagement with the teeth of said ratchet face, a support adapted to engage the teeth of said ratchet face and to interlock therewith under rearward pressure on said support, and an actuating screw operatively mounted in said support on a downward inclination and adapted to apply pressure upon said sliding jaw in the direction of said inclination, substantially as described. 110

2. In a clamping device, the combination with a bed member carrying a jaw and provided with ratchet teeth having retreating 120 inclined retaining walls, of a coöperating jaw mounted to slide on said bed member without engagement with said ratchet teeth, means for actuating said jaw, adapted to apply its actuating pressure on a downward 125 inclination, and a locking support for said actuating means, adjustable on said bed member and provided with ratchet teeth for coöperating with said bed ratchet and having the retaining walls thereof similarly in- 130

- clined, whereby the actuating means in forcing the support backward will exert a downward pressure on said support, substantially as described.
- 5   3. In a clamping device, the combination with a bed member carrying a jaw, and having a longitudinal slot formed therein, a ratchet bar secured within said slot and in spaced relation to the walls thereof, a sliding jaw mounted on said bed, a ratchet member for engagement with said ratchet bar adapted to extend into said slot upon
- each side of said bar, and an actuating screw arranged upon a downward incline with relation to the sliding jaw, whereby to apply 15 pressure thereto in the direction of the said inclination, substantially as described.
- In testimony whereof I affix my signature in the presence of two witnesses.

EBENEZER FISHER.
